CONTROL CONSOLE FOR A PHOTOCOPY MACHINE OR SIMILAR ARTICLE

Jean O. Reinecke, Glenview, Raoul E. Rodriguez, Chicago, and Robert P. Meyer, Elmwood Park, Ill., assignors to International Photocopy Corporation, a corporation of Illinois

Filed Sept. 28, 1962, Ser. No. 71,926

Term of patent 14 years

(Cl. D61—1)

FIG. 1

FIG. 2

FIG. 3

FIG. 4

FIG. 1 is a front perspective view of a control console for a photocopy machine, or similar article;

FIG. 2 is a top plan view thereof;

FIG. 3 is a front elevational view thereof, and

FIG. 4 is a right-side elevational view thereof.

We claim:

The ornamental design for a control console for a

photocopy machine, or similar article substantially as shown.
